No. 739,747.

PATENTED SEPT. 22, 1903.

C. G. TOWNSEND.

DISH MOP.

APPLICATION FILED JAN. 6, 1903.

NO MODEL.

UNITED STATES PATENT OFFICE.

CHARLES GENSS TOWNSEND, OF HOLTON, KANSAS.

DISH-MOP.

SPECIFICATION forming part of Letters Patent No. 739,747, dated September 22, 1908.

Application filed January 5, 1903. Serial No. 137,831. (No model.)

To all whom it may concern:

Be it known that I, CHARLES GENSS TOWNSEND, a citizen of the United States, residing at Holton, in the county of Jackson and State of Kansas, have invented a new and useful Dish-Mop, of which the following is a specification.

The invention relates to certain improvements in mops, and has for its principal object to provide an improved form of mop especially adapted for use in the cleansing of dishes, cooking utensils, and the like, a further object of the invention being to construct a device of this character in which boiling water or strong solutions of lye or other detergents may be employed in the cleansing process without rendering it necessary to wet the hands either in using the mop or in wringing the mop-cloth after the cleansing operation.

A still further object of the invention is to provide a mop-head with improved clamping means for engaging and holding the mop-cloth in position, while permitting the use of the device without danger of the clamping jaws or frame coming into contact with the article being washed.

A still further object of the invention is to provide a mop-head in which the cloth is engaged at one end by the fixed frame of the mop and at the opposite end by a mop-handle freely movable both circumferentially and longitudinally with respect to the mop-frame proper in order to permit the wringing of the mop-cloth and to allow the latter to fall below the frame when in use.

With these and other objects in view the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of a dish-mop constructed in accordance with my invention, illustrating the same in position for use. Fig. 2 is a face view illustrating the position assumed by the

parts during the wringing of the mop-cloth. Fig. 3 is a detail perspective view of a portion of the mop-frame.

55

Similar numerals of reference are employed to indicate corresponding parts throughout the several figures of the drawings.

The main frame of the mop-head is preferably formed of wire of a gage which may vary with the size of the mop and purpose for which it is intended, and the wire is galvanized or plated if formed of a corrosive or oxidizable material. The opposite sides of the frame 1 are formed of a pair of wire strands 2, twisted together for a portion of their length in order to add to the strength of the frame, the lower ends of the wires being separated and serving as clamping-jaws for engagement with one end of the mop-cloth 3. The jaws are preferably formed of spring-wire, and one of them is provided with a slideable cloth-engaging bar 4, having eyes or loops 5 at its opposite ends for engaging the parallel members of the jaw, and over said bar is passed the central portion of the mop-cloth, the ends thereof being thence turned, respectively, over the opposite jaw members, while the jaws are held from being separated by a clamping-bar 6, having at its opposite ends eyes or loops 7, encircling the adjacent side bars of both jaws, and when moved outwardly toward the cloth-bar serving to draw the two sides firmly together.

The upper or twisted ends of the jaws or frame are bent inwardly at a right angle to the parallel members of the frame and are thence again turned at a right angle to the first bend and are secured to a slideable sleeve 7^a, mounted on the mop-handle 8. The sleeve 9^a, which is preferably formed of copper, brass, or plated iron, is provided with rings 9, having recessed or outwardly-bent portions 10 for encircling the frame members and confining the same to the collar.

The mop-stick is freely movable within the collar and is provided at its lower end with a ferrule or ring 11, and to the end of the handle is secured an elongated loop 15.

At a point immediately above the ferrule 100 is a sleeve 16, and projecting from diametrically opposite points on said sleeve are short bars 17, terminating in loops or eyes 19, which surround the parallel members of the mop-

frame, the whole serving as a lower bearing for the mop-stick and preventing lateral play of the stick and at the same time reducing the strain on the collar to which the upper ends of the frame are secured. The sleeve is held from longitudinal movement in one direction by the ferrule and in the opposite direction by one or more lugs or pins 18, projecting from the face of the mop-stick, so that as the latter is moved vertically the guiding-bars and sleeve must move with it.

The mop-cloth should be of suitable fabric and of a size dependent on the purpose intended. The cloth is arranged in the form of a loop of any thickness, one end of the loop passing over the bar 4 and thence between the end portions of the jaw members, while the opposite end of the loop is engaged in the elongated metallic loop 15, carried by the mop-handle.

In using the mop the fingers are engaged with the substantially horizontal portions at the top of the main frame in order to hold the loop at the end of the mop-stick down near the clamping-jaws, so that the two folds of the cloth shall lie one on each side of the jaws, as shown in Fig. 1. When the top is to be dried, the handle is drawn upwardly with one hand while grasping the upper part of frame with the other until the cloth is stretched out to its fullest extent and is then turned in order to twist the cloth in the manner shown in Fig. 2, it being unnecessary to touch the cloth or to wet the fingers either in using or in wringing the water from the mop.

The device is of such character as to permit the ready cleansing of vessels of any character with scalding-water or with water containing lye or similar material injurious to the skin and may be employed in the washing of table and kitchen utensils, chambers, bath-tubs, and vessels of any character, and the mop may be made of any size, in accordance with the purpose for which it is intended.

Having thus described the invention, what is claimed is—

1. In a combined mop head and wringer a frame having clamping-jaws for engaging the mop-cloth, a relatively stationary collar secured to said frame, a mop-handle movable longitudinally and rotatably in said collar, mop-cloth-engaging means carried by the han-

dle, a sleeve encircling said handle and provided with guide-bars having terminal eyes 55 in engagement with the frame to thereby form a guide for the lower end of the mop-handle, and means for preventing independent longitudinal movement of said sleeve.

2. In a combined mop head and wringer the frame formed of sections of wire twisted together for a portion of their length and arranged to form mop-cloth-engaging jaws, a cloth-bar carried by one of said jaws for engaging the mop-cloth, a clamping-bar having 65 terminal eyes engaging both jaw members, a collar rigidly secured to the upper ends of the frame, a mop-handle guided within said collar, mop-cloth-engaging means at the lower end of the handle, and a handle-guiding means 70 comprising a sleeve encircling the lower portion of the handle and provided with projecting bars having terminal eyes for engaging the sides of the frame.

3. In a combined mop head and wringer a 75 frame formed of sections of wire twisted at their upper ends and thence bent inwardly and upwardly, a collar having means for engaging the upper ends of the twisted wire, the lower ends of the wire sections being 80 untwisted and forming a pair of clamping-jaws, a movable mop-cloth bar carried by one of said jaws and having terminal eyes engaging the parallel bars of the jaw, a movable clamping-bar having terminal eyes engaging both 85 jaw members and adjustable to clamp the jaws on the cloth and cloth-bar, a mop-handle provided at its lower end with a loop-receiving slot, an elongated loop forming the 90 mop-cloth-engaging means, a ferrule encircling the lower end of the mop-handle and serving to hold the loop in place, a handle-guiding means comprising a sleeve encircling the lower portion of the handle and having 95 diametrically opposed projecting bars provided with terminal eyes for engaging the frame, and means for preventing independent longitudinal movement of said sleeve.

In testimony that I claim the foregoing as my own I have hereto affixed my signature 100 in the presence of two witnesses.

CHARLES GENSS TOWNSEND.
